TANK SUPPORTING MEANS

Otto W. Greene, Brighton, and James Kirvan, North Chili, N. Y., assignors to Pfäudler-Permutit Inc., Rochester, N. Y., a corporation of New York

Application January 18, 1954, Serial No. 404,548

2 Claims. (Cl. 248—146)

This invention relates to supports for tanks, and more particularly to means for supporting tanks of generally cylindrical shape in horizontally extending position.

When large tanks are filled with liquid, the weight of such contents tends to change the shape of the tank, as by increasing its diameter and decreasing its vertical height, with the result that rigid supports have tended to pinch in the tank walls so as to injure its glass or other corrosion-resisting lining, or even the tank walls themselves. For the purpose of avoiding these difficulties, such tanks have been supported by bands anchored above to the building structure, but this necessitates expensive provisions in building materials and structures.

One object of the invention, therefore, is to provide supporting means for such tanks combining adequate ruggedness and strength with a requisite ability to yield or flex, to accommodate changes in shape of the tank with varying contents, or between the tank and its supports under foundation shocks and the like, without injury to the tank or its lining, or to its supporting means.

Another object of this invention is to provide improved flexible band supporting means for such tanks in which the bands are supported from below, as by relatively inexpensive leg members resting on a building floor or foundation.

A further object is to afford supporting means having the above advantages and adapted for association with tanks of the variety having corrosion-resistant linings of fused enamel, alloy metal, plastic compositions or the like, without any tendency to impair such linings.

A still further object is to provide a support of the above description capable of being readily and economically manufactured and installed.

To these and other ends the invention resides in certain improvements and combinations of parts, all as will be hereinafter more fully described, the novel features being pointed out in the claims at the end of the specification.

In the drawings:

Fig. 1 is a side elevation, partly broken away, of a tank mounted horizontally on supporting means embodying the present invention;

Fig. 2 is an enlarged, front elevation of the supporting means of Fig. 1, showing greater detail;

Fig. 3 is a side elevation of the supporting means shown in Fig. 2;

Fig. 4 is an enlarged, fragmentary section taken along line 4—4 in Fig. 2, and

Fig. 5 is an enlarged, fragmentary section taken along line 5—5 in Fig. 2.

The present embodiment of the invention, herein disclosed by way of illustration, preferably comprises a pair of oppositely arranged supports, such as shown generally at 10 in Fig. 1, disposed at or near the end of a horizontal container or tank 12. A pair of such supports is preferably employed at each end of the tank as shown, as well as at intermediate portion of its length if so desired. Tank 12 may be either cylindrical, or of oval

2

or other similar and generally rounded shape in cross section, as well understood in the art, or may be slightly tapered toward one end, as shown in Fig. 1.

Support 10 preferably comprises a welded box-like crescent-shaped leg member 22 (Fig. 2) welded or otherwise fastened to a base plate 24, which, in turn, is welded to a cylindrical bar 26 having its opposite ends projecting longitudinally beyond the plate, as shown. Bar 26 rests on foundation plate 30 and provides a pivotal support for base plate 24. The projecting ends of bar 26 are confined by two heavy steel straps 32 welded to foundation plate 30. Straps 32 serve to prevent any lateral or longitudinal movement of bar 26 or its attached plate 24, but leave these parts free to rock to a limited degree. Plate 30 is shown as composed of two thicknesses welded together, with the extending lower thickness fastened to a concrete floor or foundation base 34 by means of suitable bolts 36.

The curved portion of each crescent-shaped member 22 comprises a steel plate 40 preferably curved and inclined to the horizontal, upwardly and outwardly, to conform substantially to the shape of the tank, as, for example, in the form of an arc of a circle whose radius is approximately equal to the radius of tank 12. A resiliently flexible steel strap or band 42, is welded to spaced parts at the upper and lower ends of plate 40, as shown at 44 and 46 in Fig. 2. The central portion of band 42 is similarly curved but shorter than the corresponding part of plate 40, so that the intermediate portions of said band will be spaced from plate 40 at all points between points 44 and 46. The lower end of band 42 projects beyond the lower end 46 of plate 40 and is bent upwardly at a small angle, as shown and hereafter described.

Tank 12 is provided with bands 48 preferably of steel about one sixteenth ($\frac{1}{16}$) of an inch less in thickness than the tank wall and partially or wholly encircling the tank. It preferably employ encircling bands which are drawn tight by means of bolts 50 engaging angle pieces 52 attached to the spaced ends thereof and securely anchoring the bands in place, as shown in Fig. 3. A layer of roofing paper or other similar frictional cushioning material 54 (Figs. 4 and 5) is placed between bands 48 and the tank to cushion the area of contact and to take up small irregularities of the parts. In the case of a tapered tank, an additional piece of cushioning material 56 may be placed under one side of each band 48 to allow for the change of diameter between the cylindrical inside surface of the band 48 and the slightly conical outside surface of the tank, as shown in Fig. 4.

Tank 12 is placed on the supports or leg means 10 with the tank bands 48 resting on the leg bands 42, as shown in Fig. 2, and made fast by welding the lower ends 60 and the intermediate portion 62 of bands 42 to the adjacent portions of bands 48. Tank 12 is thus yieldingly and resiliently cradled on bands 42 which, in turn, are carried by supports 10. Since the latter have a limited rocking movement in a lateral plane together with their cylindrical bars 26, all tank stresses are relieved by the combined flexing of bands 42 and a corresponding rocking movement of the supports 10.

The invention thus provides means for yieldably and strongly supporting a tank of the above character adjacent its head portions at which it has the greatest strength, or at intermediate portions if desired. The supporting means is capable of an adequate degree of resilient yielding to varying longitudinal and circumferential stresses, so as to accommodate variations in the shape of a tank with variations in its contents and weight, without injury to the tank or its corrosion-resisting lining, as well as to accommodate variations in

stresses between the tank and its foundations which may be caused by any shifting of such foundations, and these advantages are afforded by a simple and practical type of construction associated with the tank in such a way as to avoid any welding of supporting parts to the tank wall or other means of attachment capable of injuring the tank or its fused enamel or other protective lining.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the constructions and arrangement of the parts will readily occur to those skilled in the art, within the spirit of the invention and the scope of the appended claims.

We claim:

1. The combination with a liquid storage tank of generally rounded, cross-sectional shape disposed with its longitudinal axis extending in a generally horizontal direction, of a plurality of pairs of supporting legs spaced longitudinally of said tank with the legs of each pair spaced from each other on opposite sides of said axis, and a band in encircling attachment to said tank at each of said pairs of legs, each of said legs comprising a base portion, a body portion pivotally mounted on said base portion independently of the other leg of said pair and having a portion inclined upwardly and outwardly of said tank, said inclined portion being shaped to extend partially around the perimeter of said tank encircling band laterally of and above the tank bottom and having spaced parts and a flexible leg band having its opposite ends attached to said spaced parts of said inclined body portion, respectively, with the intermediate part of said

leg band spaced from said inclined body portion and attached to said tank encircling band for yieldably supporting said tank in floating relation to said body portion.

5 2. A support means for supporting a tank of generally rounded, cross-sectional shape disposed with its longitudinal axis extending in a generally horizontal direction, said support means comprising a band for encircling attachment to said tank, at least one leg means supporting said tank-encircling band, said leg means comprising a base portion, a body portion pivotally mounted on said base portion and having a portion inclined to the horizontal, said inclined portion being shaped to extend partially around the perimeter of said tank band and having spaced parts, and a flexible band having its opposite ends attached to said spaced parts of said inclined body portion, respectively, with the intermediate part of said band spaced from said inclined body portion and said flexible band being fixed to said tank-encircling band for yieldably supporting said tank in floating relation to said body portion.
